UNITED STATES PATENT OFFICE.

JOHN ELWOOD WILSON, OF PHILLIPSBURG, NEW JERSEY.

TOY.

1,283,390.

Specification of Letters Patent. Patented Oct. 29, 1918.

Application filed July 24, 1917. Serial No. 182,560.

To all whom it may concern:

Be it known that I, JOHN E. WILSON, a citizen of the United States, residing at Phillipsburg, in the county of Warren and 5 State of New Jersey, have invented new and useful Improvements in Toys, of which the following is a specification.

This invention comprehends the provision of a toy having the general appearance of a pistol, and in the barrel of which is arranged a fan normally folded and concealed from view, but which when the trigger is actuated, is suddenly unfolded and exposed in a manner quite amusing to the 15 one handling the toy.

The nature and advantages of the invention will be better understood when the following detail description is read in connection with the accompanying drawing, the 20 invention residing in the construction, combination and arrangement of parts as claimed.

In the drawing forming part of this specification like numerals of reference indicate 25 similar parts in the several views and wherein:—

Figure 1 is a view of the toy in elevation.

Fig. 2 is an end view.

Fig. 3 is a vertical longitudinal sectional 30 view therethrough showing the parts in their normal position.

Fig. 4 is a rear end elevation.

Fig. 5 is a side elevation showing the position of parts subsequent to actuating the 35 trigger.

Fig. 6 is a transverse sectional view.

Referring to the drawings in detail A indicates a pistol-shaped body, comprising a handle 10 upon one end of which is arranged 40 an elongated member 11 which is disposed substantially at right angles to the handle 10 and projects beyond the opposite sides thereof. The member 11 has one side channeled as at 12 to accommodate the barrel 45 of the pistol, the barrel projecting an appreciable distance beyond one end of the member 11, and terminating short of the opposite end as shown. The barrel comprises two sections, one section 13 being 50 fixed relatively to the member 11, while the other section 14 is pivotally associated with the section 13 at their corresponding rear extremities. The section 14 may be pivotally connected with the section 13 in any suitable manner, which will permit the section 14 to swing upwardly and rearwardly 55

to a position to lie upon the member 11 in alignment with the section 13 as clearly illustrated in Fig. 5.

A trigger mechanism is employed for holding the sections associated to define a barrel, and to permit of a release of the section 14 when the finger engaging element of the trigger mechanism is actuated. As shown in this specific instance the trigger mechanism embodies a rod 15 disposed beneath the section 13 of the barrel for sliding movement longitudinally thereof, the rod operating in a groove 16 in the member 11, so that the rod will be guided in its movements. Secured to the under side of the section 13 of the barrel is an eye 17 through which the rod passes, the eye serving to maintain the forward extremity of the rod properly positioned with respect to 75 the corresponding extremity of the barrel for the purpose to be presently described. The forward extremity of the rod 15 is bent at right angles as at 18 and projects through a slot 19 in the section 13 of the 80 barrel, and terminates to provide a hook 20 disposed substantially in a plane with the longitudinal center of the barrel. Carried by the forward extremity of the section 14 of the barrel is a loop 21 which is adapted 85 to be engaged by the hook 20 to maintain the sections 13 and 14 associated in barrel-like formation. The opposite extremity of the rod 15 is bent at an angle and passes through an elongated slot 22 in the member 90 11, this angularly disposed portion providing a finger engaging element 23 through the instrumentality of which the rod 15 is actuated to effect a release of the section 14. A leaf spring of substantially L-shaped formation is employed to maintain the rod 15 at the limit of its movement in one direction, in which position of the rod the loop 95 21 is engaged by the hook 20. One branch 24 of said spring is secured in any suitable 100 manner on the member 11, while the remaining branch 25 of said spring projects through the slot 22 and bears against the finger engaging element 23 as shown.

With a view of automatically swinging 105 the section 14 of the barrel to the position illustrated in Fig. 5, subsequent to the release of said section from the section 13, I make use of a coil spring 26 which is wholly disposed within a bore 27 in the handle 10. 110 One end of the spring is secured to a pin 28 intersecting said bore, while projecting

from the opposite extremity of the spring is an arm 29 which normally extends above the member 11 and connects with the section 14. The arm 29 when the parts are in the 5 position disclosed in Fig. 1, maintains the spring 26 under tension, so that when the finger engaging element is retracted to effect a release of the section 14 of the barrel from the section 13, the spring 26 contracts and 10 suddenly and quickly moves the section 14 about the pivot to the position illustrated in Fig. 5. As shown in Fig. 5 a fan 30 is used in conjunction with the invention, one end of the fan being secured to the fixed 15 section 13 of the barrel, while the opposite end of the fan is secured to the movable section 14. When the sections are associated the fan is folded and being wholly disposed within the barrel, is concealed from view. 20 The fan may be striped to represent the American Flag, or given some other ornamental appearance which is pleasing to the eye. When the top is handled by persons unfamiliar with its construction, the finger 25 engaging element retracted, the section 14 of the barrel together with the fan 30 will suddenly assume the position illustrated in Fig. 5 to the amusement of those present. The toy may be constructed of any suitable 30 material, and vary in design without departing from the spirit of the invention.

While it is believed that from the foregoing description the nature and advantages of the invention will be readily apparent, I 35 desire to have it understood that what is herein shown is merely illustrative, and that such changes may be resorted to when desired as fall within the scope of what is claimed.

40 What is claimed is:—

1. In a toy of the character described, a pistol including a sectional barrel, one of 45 said sections being movable relative to the other and pivotally connected thereto, mechanism for holding said sections associated to define said barrel, a trigger forming part of said mechanism for effecting a release of said movable section, and said movable section being capable of assuming a position in 50 axial alignment with said fixed section when released.

2. In a toy of the character described, a pistol including a sectional barrel, one of 55 said sections being movable relative to the other and pivotally connected thereto, means for holding said sections associated, means for effecting a release of said movable section, and means for automatically swinging said movable section about its pivot to a 60 position in axial alignment with the fixed section.

3. In a toy of the character described, a pistol including a sectional barrel, one of 65 said sections being movable relative to the other and pivotally connected thereto at one

end, coöperating means carried by the opposite extremities of said sections for holding said sections associated, means for effecting a release of said movable section, and means for automatically swinging said 70 movable section upon its pivot to a predetermined position subsequent to the release of said section.

4. In a toy of the character described, a pistol including a sectional barrel, one of 75 said sections being movable relative to the other and pivotally connected thereto at one end, coöperating means carried by the forward extremities of said sections for holding the latter associated, and means for 80 automatically moving said section about its pivot to a predetermined position.

5. In a toy of the character described, a pistol including a sectional barrel, one of 85 said sections being movable relative to the other and pivotally connected thereto, mechanism for holding said sections associated, a trigger forming part of said mechanism for effecting a release of said movable section, and yieldable means connected with 90 said movable section for automatically swinging the latter upon its pivot to a predetermined position when released.

6. In a toy of the character described, a pistol including a sectional barrel, one of 95 said sections being movable relative to the other and pivotally connected thereto adjacent one end, a loop carried by the forward extremity of said movable section, a rod slidably associated with the fixed section and having a hook-like extremity engaging said loop to hold said sections associated, a finger engaging portion forming part of said rod whereby the latter may be operated to effect a release of said movable 105 section, and means for moving said movable section about its pivot to a predetermined position when released.

7. In a toy of the character described, a pistol including a sectional barrel, one of 110 said sections being movable relative to the other and pivotally connected thereto adjacent one end, coöperating means carried by said sections for holding the latter associated, said means including a reciprocating 115 rod having a finger engaging portion, whereby said rod may be operated to effect a release of said movable section, a yieldable means bearing against said finger engaging portion of said rod for holding the latter 120 normally in active position, and means for swinging said movable section about its pivot to a predetermined position when released.

8. In a toy of the character described, a 125 pistol including a sectional barrel, one of said sections being movable relative to the other and pivotally connected thereto, means for holding said sections associated, and means for effecting a release of said movable 130

section, a handle, a yieldable means embedded in said handle, and a connection between said yieldable means and the movable section whereby the latter is automatically 5 swung about its pivot to a predetermined position when released.

9. In a toy of the character described, a pistol including a sectional barrel, one of said sections being movable relative to the 10 other and pivotally connected thereto, means

for holding said sections associated, and means for effecting a release of said movable section, a handle, and a yieldable means embedded in said handle, a connection between said yieldable means and the movable 15 section whereby the latter is automatically swung about its pivot to a predetermined position when released.

In testimony whereof I affix my signature.
JOHN ELWOOD WILSON.
